UNITED STATES PATENT OFFICE.

WILLIAM LUEDER, OF SAN FRANCISCO, CALIFORNIA.

SHIP'S DAVIT.

1,173,821.

Specification of Letters Patent. Patented Feb. 29, 1916.

Application filed June 10, 1915. Serial No. 33,292.

To all whom it may concern:

Be it known that I, WILLIAM LUEDER, a subject of the Emperor of Germany, residing at 363 Second avenue, San Francisco, 5 in the county of San Francisco, State of California, have invented a new and useful Ship's Davit, of which the following is a specification in such full and clear terms as will enable those skilled in the art to construct and use the same.

This invention relates to a davit for ships and one of the objects of the invention is to provide means whereby a series of davits may be operated all at once to swing the 15 boats clear of the ship in time of necessity, separate means being provided for lowering each boat of the entire series operated by the swinging mechanism.

Another object of the invention is to 20 provide means whereby the lashings of each boat will be released at the same time when the davits start to swing out from the ship.

Another object of the invention is to provide automatic means for retarding the lowering of the boat thereby preventing accidents due to too rapid lowering of the boats into the sea, separate means being provided for manually stopping the descent of the boat should that be required at any time.

30 In the drawings, in which the same reference numeral is applied to the same portion throughout the several views, there is shown one embodiment of the invention, although there may be many modifications 35 thereof.

Figure 1 is a view in section of a portion of the boat deck of a ship having this davit applied thereto and showing a diagrammatic view of life boat in place, Fig. 2 is a plan view of the parts shown in Fig. 1 with the false deck removed for purposes of illustration, Fig. 3 is a longitudinal view of the boat and davit the ship deck being in section, and Fig. 4 is a detail partly in section 45 showing the brakes.

The numeral 1 illustrates the hull of the ship, 2 indicating the deck of the ship on which the davits 3 and 4 are supported. The davits are stepped in suitable bearings in 50 the deck 2 as indicated at 4 and 5, the davit 3 having a segment worm gear 6 and the davit 4 having a worm gear 7, each of said gears being adjacent the bearings for the davits. Above the said gears there is a 55 false deck 9 supported on stringers 10 and 11. Extending through the false deck are

two chock blocks 12 and 13 for the support of the boat, the boat keel being held against said chock blocks by means of the movable chocks 14 and 15 which are pivoted in bearings 16 and 17 on the main deck 2. Extending along the deck of the ship is a shaft 18, said shaft serving such a number of boats as it may be desired to be applied to and receiving power from any suitable source, not shown. 60 The shaft 18 has four bearings 19, 20, 21 and 22 and it is provided with two worms 23 and 24, the former slideable on a feather 25, a collar 26 on the shaft preventing said worm 23 from moving to the left with respect to 70 said shaft any more than it is shown in Fig. 2. The gear 7 has a shoulder 27 projecting into the hole at its center, which shoulder is intended to meet a cam 28 on the side of the davit 4 when the gear has 75 rotated to the left the same amount as the gear 6 has rotated to the right, see Fig. 2. The gear 7 is only connected with the davit 4 when its shoulder 27 contacts with the cam 28 and it is used both to force the davit 80 4 to the left after reaching the outboard position, as well as to pull the davit 3 to the right when reaching its ultimate travel, the worm 23 at that time being moved along the feather 25. 85

The worm 24 is rigidly connected with the shaft 18 and continuously rotates the gear 7 until the davit arm 4 turns as much as may be necessary to swing the boat over the side of the ship, but the worm 23 is slideable on 90 the shaft 18 so that as the davit arm 4 is rotating from the position in which it is pointing directly toward the gear 6 it draws the davit arm 3 to the right, Fig. 2, at which time the worm 23 moves along the shaft 18, 95 such an amount as it may be necessary to allow the arm 4 to move to the desired position, the letters A', A'', B', B'', C', C'' indicating the successive positions of the davit arms in moving from the inboard to the outboard positions. Below the false deck 9 and on the main deck 2 are mounted guide blocks 30-31-32-33 for 2 slideable bars 35-36. Each of the slideable bars is provided with a series of rack teeth which teeth are in engagement with pinions 37-38 on the shaft 18. Each of the rack bars is also provided with two hooks as indicated at 39 and 40, said hooks being for the purpose of holding the links 41-42 connecting with the lashing 105 cables 43-44, which cables have hooks 45 and 46 passing over the gunwale of the boat 110

2
 "B". There are a pair of the lashing cables and hooks at each end of the boat. In order to hold the teeth on the bars 35-36 in engagement with pinions operating them each 5 of the bearing blocks 20 21 for the shaft 18 has a bracket 47 on its side, one bracket for each of the bars 35-36.

Mounted on the deck inboard from the life boat is a shaft 48, said shaft having 10 suitable journal bearings bolted to the deck and carrying drums 49-50 for the cables 51-52, said cables passing over pulleys 53 at the top of the davit arms, 54 at the center of the curve thereof, 55 at the top of the 15 straight portion thereof, and 56 on the deck 1. The shaft 48 is provided with a large pinion 58 in mesh with a small pinion 59 on the shaft of the motor M and said motor being controlled from the switch box 60.

20 In order to provide automatic means for preventing the boats from being lowered too rapidly the shaft 61 of the motor is extended far enough to carry the governor arm 62-63 which arms are connected with a collar 64 25 which collar is connected by a suitable linkage to a vertical shaft 65 having an arm 66 connected to a band brake 67, which bears on the bottom of the brake wheel 68. The shaft 61 is also provided with a brake wheel 30 69 around which passes the brake band 70 operated by means of the hand lever 71 to enable the person lowering the boat to stop the same whenever necessary the segment 35 rack 72 providing means by which the brake may be left set at any desired point.

The operation of the davit is as follows: When the boat is to be lowered the shaft 18 is rotated. This first releases the boat lashings and the chocks by moving the bars 35, 40 36 longitudinally, the gears moving said bars only a short distance. The shaft continues to rotate and as it does so positively drives the gear 6 until the davits assume the position A' A''. The davit in the position 45 A' then is met by the cam 27 and along with the other davit is positively rotated clockwise. The davit 4 is positively rotated something over 200 degrees. When the davits assume the positions B' B'' it is 50 necessary for the davit 4 to rotate about 90 degrees; but the davit 3 may then be backed up because the gear 23 is free to slide to

Copies of this patent may be obtained for five cents each, by addressing the "Commissioner of Patents, Washington, D. C."

the right on the shaft 18, but that davit will not move as much as the other one since some of the motion is lost by reason of the 55 supporting ropes inclining in certain of the positions. When the boat has been swung out from the ship the motor or other hoisting apparatus may be operated to raise the boat, or, if the boat is to be lowered, it may 60 be accomplished by operating the brake alone.

Having thus disclosed my invention, what I desire to secure by Letters Patent of the United States, is as follows, modifications 65 within the scope of the claims being expressly reserved:

1. A life boat handling apparatus comprising the combination with a support for the boat, of lashing lines and chocks for the boat, a pair of ships' davits to which supporting cables from each end of the boat extend, a shaft extending to both of the davits, a slideable worm and a fixed worm on said shaft, a gear on each davit in mesh 70 with said worms whereby the davits may be turned outboard, a pair of slides for holding the lashings and chocks, and a pair of pinions on the shaft for moving said bars to release the lashings and chocks. 75

2. A life boat handling apparatus comprising the combination with a support for the boat, of lashing lines and chocks for the boat, a pair of ships' davits to which supporting cables from each end of the boat 80 extend; a shaft extending to both of the davits, a slideable worm and a fixed worm on said shaft, a gear on each davit in mesh with said worms whereby the davits may be turned outboard, a pair of slides for holding the lashings and chocks, a pair of pinions on the shaft for moving said bars to release the lashings and chocks, drums 85 over which the boat cables pass from the davits, and a manually operated brake for 90 retarding the descent of the boat. 95

In testimony whereof I have hereunto set my hand this 28th day of May A. D. 1915, in the presence of the two subscribed witnesses.

WILLIAM LUEDER.
